UNITED STATES PATENT OFFICE.

HIRAM A. BARRETT, OF KNOXVILLE, ILLINOIS.

TANK HEATER.

1,408,680.

Specification of Letters Patent.

Patented Mar. 7, 1922.

Application filed February 24, 1921. Serial No. 447,420.

To all whom it may concern:

Be it known that I, HIRAM A. BARRETT, a citizen of the United States, residing at Knoxville, in the county of Knox and State 5 of Illinois, have invented certain new and useful Improvements in Tank Heaters, of which the following is a specification.

This invention relates to stock-watering tanks and has special reference to means for 10 heating the water in the tank so that it will be prevented from freezing and will be maintained at a temperature suitable for drinking by the stock. The invention seeks to provide a novel and efficient heater by the 15 use of which a circulation of the water in the tank will be effected and the entire body of the same, therefore, heated. The invention also seeks to provide a heater of such construction that air will be admitted to the 20 heater in sufficient volume to support combustion and permitted to escape so that accumulation of foul air in the heater will be avoided. The invention further seeks to provide a heater for the stated purposes 25 which will be inexpensive and may be readily employed within any tank.

The invention is illustrated in the accompanying drawings and will be hereinafter fully set forth, and in the said drawings—

30 Figure 1 is a longitudinal vertical section of a heater embodying my invention and arranged within a tank;

Fig. 2 is a detail transverse section of the water back;

35 Fig. 3 is a view partly in elevation and partly in transverse section.

In the drawings, a portion of the tank is shown at 1 and the heater is shown as resting directly upon the bottom of the tank.

40 The heater comprises a shell or casing 2 having a main portion projecting above the water line in the tank and preferably above the top of the tank. The casing is further provided with an offset or extension 3, the 45 top of which is below the water level and within which is supported a water back 4 and burners 5. The burners 5 may be of any well-known type of oil burner and will preferably be arranged in pairs, as shown most 50 clearly in Fig. 3, each burner being equipped with a chimney or flue 6 so that the heat from the burner will be directed against the bottom of the water back 4 which is supported within the offset 3 above and over the 55 burners. The water back is a closed com-

partment resting upon brackets 7 secured upon the inner surface of the shell or casing of the heater and the bottom of the water back is corrugated, as shown at 8, whereby an extended heating surface will be presented to the action of the hot currents rising from the burners 5 and the water in contact with the said corrugated bottom will be quickly raised in temperature. It will be readily noted that the corrugated formation 60 of the water back bottom provides lower channels or grooves in which the heat from the burners will be confined and also provides upper channels or grooves which receive portions of the water in the water back 65 so that within a comparatively small area of the heater, a large heating surface will act upon the water so that the water will be quickly heated and circulation of the same 70 will ensue. From one end of the water back, 75 an inlet nozzle or pipe 9 extends through the adjacent wall of the shell and this nozzle has its outer end downturned, as shown clearly in Fig. 3. At the opposite end of the water back, an outlet 10 leads through the 80 adjacent wall of the shell or casing 2 and this outlet nozzle is extended upwardly and will preferably terminate at or slightly above the normal water level of the tank. It will be readily understood that as the bottom of 85 the water back is exposed to the direct action of the heat from the burners 5, the water resting upon the bottom of the water back will be soon raised in temperature and will pass out through the outlet nozzle 10 and be 90 discharged onto and commingle with the main body of water in the tank. As heated water leaves the water back, cooler water will flow into the same and it will be readily noted that as the inlet nozzle is turned down- 95 wardly outside the casing 2, the water entering the said nozzle will come from a level near the bottom of the tank and, therefore, a thorough circulation of the water in the tank will be set up.

100 Fuel is supplied to the burners 5 through a pipe 11 supported upon the floor of the heater or in any other preferred manner and communicates with the burners through branches 12. The pipe 11 is connected directly with a supply tank or reservoir 13 which may be supported in any desired manner within the shell 2 at a point remote from the burners, and between the reservoir and the burners, I provide a partition 14 which 105 110

divides the interior of the main portion of the casing into two vertical flues so that a circulation of air to and from the burners will be maintained. The partition 14 extends to a point near the top of the main body of the shell or casing 2 and rests at its lower corners upon the bottom of the casing but is provided at its lower end with an elongated notch or slot 15 to accommodate the supply pipe 11 and also to permit circulation so that cold fresh air may pass to the burners. In the present instance, I have shown the main body of the heater as covered by a lid 16 which rests on and fits closely within the upper end of said body and is provided with a handle 17 whereby it may be easily removed and replaced. The lid is preferably of an arched form and is provided in its ends with a plurality of openings 18 through which air is permitted to enter and to escape. It will be understood, of course, that the nozzles 9 and 10 are threaded into the ends of the water back so that they may be easily removed when it is desired to remove the water back from the casing and as easily replaced after the water back has been returned to its operative position.

It is essential to support combustion that air be constantly supplied to the heating chamber. My device very effectually provides for the admission of fresh air and the escape of heated air from the casing so that combustion at the burners will take place as long as the supply of fuel is not exhausted. When a flame has been produced at the burners, the heat therefrom will rise through the chimneys or tubes 6 and will strike against the bottom of the water back, being deflected by the same and then passing rearwardly therefrom toward the partition 14. The partition will, of course, prevent the warm currents reaching and playing upon the reservoir 13 and they will naturally ascend through the relatively narrow space or flue between the partition and the wall of the casing adjacent the offset 3, eventually escaping through some of the openings 18 in the cover. This flow of hot air from the heater will create a draft around the reservoir and between the wall of the heater and the partition 14 so that fresh cool air will be drawn into the heater through the openings 18 and play upon the reservoir to aid in guarding against explosion. The descending cool air currents will obviously pass through the slot or notch 15 at the lower edge of the partition and will thence pass to and upwardly around the burners so that combustion will be maintained and a circulation within the heater created. It will be readily noted that by providing openings in the end walls of the cover, I check the entrance of air so that the draft through the heater will not be excessive and, therefore, will not tend

to extinguish the flame but, by providing the partition 14, I create a positive circulation of air through the casing so that the foul air and products of combustion may escape but fresh air will be constantly admitted to support combustion. Moreover, by retarding the draft or circulation, the air within the heater adjacent the water back will be thoroughly heated and will act upon the side walls of the offset portion of the heater as well as upon the end walls thereof to heat the same and thus act directly upon the body of water in the tank.

The heater need not be permanently secured within the tank but may rest directly upon the bottom thereof and may be placed at any point of the tank. It may also be removed and replaced at will so that the cleaning of the heater may be very easily and thoroughly accomplished. When the burners need attention, the partition and reservoir are removed, after which the burners may be readily drawn back from the offset 3 and lifted out through the top of the main body of the casing. The device is very simple in the construction and arrangement of its parts, may be produced and installed at a low cost, and in use will be found highly efficient.

Having thus described the invention, what is claimed as new is:

1. A heater for stock-watering tanks comprising a shell having an offset portion at one side, a burner within the offset portion of the shell, and a water back supported within the offset portion of the shell directly over the burner and having inlet and outlet nozzles at its opposite ends in communication with the water in the tank.

2. A heater for stock-watering tanks comprising a casing adapted to be supported within a tank, a burner within the casing, a water back supported within the casing and exposed to the direct action of the burner, an inlet nozzle extending from one end of the water back near the bottom thereof through the adjacent wall of the casing and turned downwardly at the outer side of the casing, and an outlet nozzle leading from the opposite end of the water back near the top thereof through the adjacent wall of the casing and turned upwardly at the outer side of the casing.

3. A heater for stock-watering tanks comprising a casing adapted to be supported within a tank and having a main portion extending above the water level in the tank and an offset portion extending laterally from the lower end of the main portion, a fuel reservoir within said casing, a burner within the offset portion of the casing spaced from and in communication with the reservoir, a water container disposed above the burner and in communication with the water in the tank, and a partition arranged within

and extending to the top of the main portion of the casing between the burner and the fuel reservoir.

4. A heater for stock-watering tanks comprising a casing adapted to be supported within a tank and including a vertically extending main portion and a lateral offset extending from the lower part of the main portion, a vertically disposed partition within the main portion of the casing resting on the bottom thereof and extending to the top of the same, said partition having an open-

ing through its lower portion, a fuel reservoir supported within the tank at one side of said partition, a burner within the offset 15 of the casing at the opposite side of the partition and in communication with the reservoir, a water container supported directly over the burner, and a cover removably fitted upon the casing directly over the partition and provided with a plurality of openings therethrough.

In testimony whereof I affix my signature.

HIRAM A. BARRETT. [L. s.]
